(57) CLAIM

The ornamental design for a cover for stadium seat, as shown and described.

DESCRIPTION

FIG. 1 is a perspective view of a cover for stadium seat.

FIG. 2 is a front view of a cover for stadium seat.

FIG. 3 is a bottom view of a cover for stadium seat; and, FIG. 4 is a side view of a cover for stadium seat.

The broken lines are for the purpose of illustrating the environment of the design only and form no part of the claimed design.
